(57) **CLAIM**

The ornamental design for a portable potty, as shown and described.

DESCRIPTION

FIG. 1 is a front, left, and bottom perspective view of a portable potty, showing my design.

FIG. 2 is a rear and right perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof.

FIG. 8 is a bottom plan view thereof; and,

FIG. 9 is a perspective view of portable potty similar to FIG. 2, but feet of the portable potty are folded up.

The broken lines shown in the drawings are included for the purpose of illustrating portions of the portable potty that form no part of the claimed design.
